PAPER MACHINE DRYER DRUM

Eugene S. Skinner, Beloit, Wis., assignor to Beloit Iron Works, Beloit, Wis., a corporation of Wisconsin

Filed Mar. 3, 1960, Ser. No. 12,551

3 Claims. (Cl. 34—124)

The instant invention relates to a dryer drum for a paper machine, and more particularly, to an improved dryer drum structure. As conventionally employed in the art, dryer drums for paper machine drying sections generally consist of a cylindrical shell, spaced heads extending radially across the shell to close the open ends thereof and carrying means for journaling the shell for rotation, and means for introducing steam into the interior of the shell and drawing condensate therefrom. The Yankee dryer drum has generally the same structural arrangement as now used in the art, except that the Yankee dryer drum is ordinarily of substantially greater size than the dryer drums in the conventional dryer section of a paper machine. Nevertheless, in each case these dryer drums (whether the large Yankee dryer drum or the smaller conventional drum) have certain operating limitations.

In the prior art paper machine dryers, steam is admitted to the interior of the dryer and is in contact with the entire interior surface of the dryer, the inner cylinder wall being subject, therefore, to uniform temperature. Condensate forms on the inner surface of the cylinder and the condensate layer depth is substantially uniform at the minimum thickness or depth obtainable with siphon equipment used. The outer wall of the dryer, however, is subject to variations in temperature. For example, the moist paper web may not extend the full length of the cylinder shell, so as to leave the ends thereof uncovered by the paper. Also, the paper web passing over the cylindrical shell may not be dried to the same extent in the central portion as it is at the edges thereof. In addition, the rate of water evaporation from the web may vary across the width thereof, because of prior irregularities in the processing of the web, or different characteristics in the web, or different draft conditions in the dryer part. In particular, however, the dryer surface in the region of the heads is not cooled by the passing damp sheet and it is subjected to cooling only from the ambient air which, of course, may vary greatly in relative humidity and/or temperature. In general, the cooling effect at the end reaches of the shell is less than that in the intermediate portion.

The instant invention provides a simple and economical means for overcoming this difficulty. It will be appreciated that the tendency for the ends of the shell to become overheated, or more greatly heated than the intermediate portion, results in a tendency to overdry the edges of the web adjacent thereto, and causes an unnecessary heat loss. In the instant invention, however, insulating means are provided along the inner periphery of the end portions of the shell to reduce heat transfer from the steam to the shell body in these regions. It will be appreciated that the instant invention may be employed to reduce heat transfer from the steam to any particular portion of the shell desired, although the main problem here solved is that of reducing heat losses at the shell ends and reducing overheating of the shell ends.

In U.S. Patent No. 2,893,136, issued July 7, 1959, in the names of Edgar J. Justus and Robert A. Daane, one solution to this same problem is provided. In the patented arrangement a plurality of circumferential dams are mounted on the inner periphery of the dryer shell at axially spaced locations therewithin. One dam is aligned approximately with the extreme edge of the paper web trained about the shell outer periphery, and another cir-

2

cumferential dam or annular ridge may be located in closely spaced relation to the first dam or ridge so as to align a space therebetween with the edge portion of the paper web. The circumferential dams maintain levels of condensate against the inner periphery of the dryer drum shell, and the condensate levels are effective as insulators to reduce the rate of heat transfer from the live steam within the shell to the outer shell periphery, thereby readily, simply and economically reducing heat losses to the ambient atmosphere.

The instant invention is even more economical to fabricate and install than the Justus et al. patented structure, and features insulating members or bands of asbestos, fiber glass or like tape materials carried upon the shell inner periphery at generally the locations of the condensate levels L and l in Justus et al. 2,893,136. The insulating bands may be provided by a layer of insulating medium lying generally flush against the shell inner periphery and secured by adhesive means or in any other suitable manner to a metallic band, the ends of which may mount clamping means or like devices. The insulating means are economical to fabricate, may be readily installed and removed, and since both the fibrous insulation and metal band are rather poor heat conductors, the rate of heat transfer from the live steam within the shell to the outer shell periphery is markedly reduced.

It is accordingly an important aim of the instant invention to provide an improved dryer drum structure.

Another object of the instant invention lies in the provision of an improved dryer drum having insulating means therein to reduce the heat transfer rate from the heating fluid in the dryer drum to the dryer outer periphery.

A further object of the present invention is to provide a dryer drum comprised of a shell and insulating means carried along the shell inner periphery in close contact therewith, the insulating means including a fibrous band member and a metallic band support therefor, whereby selected portions of the dryer drum shell are effectively insulated to reduce heat transfer losses during various operating speeds of the dryer drum.

Other objects and advantages of the invention will become more apparent during the course of the following description, particularly when taken in connection with the accompanying drawings.

In the drawings, wherein like numerals designate like parts throughout the same:

FIGURE 1 is a partial sectional elevational view of a dryer drum constructed in accordance with the principles of this invention;

FIGURE 2 is a fragmentary plan view of insulating means embodying the concepts of this invention; and

FIGURE 3 is a fragmentary detail sectional view taken substantially along the line III—III of FIGURE 2, 55 with the clamping means thereof shown in elevation.

Referring now to the drawings, a dryer drum of the instant invention is designated generally by the numeral 10, although in FIGURE 1 only the lower half of the drum is shown in sectional elevation for simplification of the description of this invention. The dryer drum 10 comprises a cylindrical shell 11 having open ends closed by annular heads 12 and 12a which are secured to the ends of the shell by bolts 13 and extend radially across the ends of the shell 11. Journals 14 and 14a are shown as integrally formed with the heads 12 and 12a, the journals extending axially outwardly therefrom to be received by suitable bearings (not shown) for rotatably mounting the drum 10. An axial bore 15 and 15a extends through each journal 14 and 14a, while in the particular structure illustrated, the axial bore 15a is closed off by a plate 16a. At the opposite end of the drum 10 the axial bore 15 mounts a plate 16 which receives a steam inlet header 17

connected to a suitable source of steam S, shown diagrammatically. The steam flows from the source S through the steam inlet line 17 leading into the shell 11 through the head 12, and it may be seen that the steam enters the shell interior through an apertured head 18.

The steam within the shell 11 is continuously condensed, and the condensate deposits as a film on the inner periphery of the shell 11. The condensate thus formed collects along the shell inner periphery and is maintained thereagainst in a generally uniform thickness of liquid by reason of centrifugal force resulting from rotation of the dryer drum 10. A syphon nozzle 19 placed against the central inner periphery of the shell 11 picks up condensate and returns the same to a radially aligned pipe 20 connected to a central condensate header 21, which in turn is concentrically mounted within the steam inlet header 17 and passes out through the shell head 12 into suitable receiving means such as a drain D, shown diagrammatically.

The dryer drum 10 as thus far described is representative of a typical prior art structure. It is of course appreciated that the steam inlet line may lead through one head and the condensate line through the opposite head, and as well, other variations may be practiced in the arrangement of the elements, consistent with the knowledge of the prior art. The present invention is directed particularly to means for controlling the heat transfer through the shell 11 at various points or locations. As is indicated in FIGURE 1, a web W is trained about the outer periphery of the shell 11, however, this web W leaves exposed end portions 11a and 11b of the shell 11, which are cooled only by ambient atmosphere. The web edges Wa and Wb may also be more dry than the main body of the web W, or may be inclined to dry more rapidly, if subjected to the same amount of heat.

In accordance with the principles of this invention, a first pair of insulating means 22 and 23 are mounted on the inner periphery of the shell 11 at the shell ends 11a and 11b adjacent the heads 12a and 12, respectively. It may be seen that inner edge 22a of the insulating means 22 is approximately aligned with the marginal portion of the web edge Wa, while inner edge 23a of the insulating means 23 is similarly approximately aligned with the extreme edge of the web edge portion Wb, so that at opposite ends of the shell 11 heat insulating barriers are provided lying generally over the end portions 11a and 11b of the dryer shell. In other words, the insulating members or bands 22 and 23 extend a sufficient distance or are of sufficient width to overlie the major portion of the axial length of each shell end portion 11a and 11b and have their inner face positioned to contact the steam so that heat transfer from the live steam within the shell 11 to the outer shell periphery in these regions 11a and 11b is markedly reduced. Thereby, heat losses to the ambient atmosphere through the shell end portions are minimized.

Located closely adjacent the insulating means 22 and 23, and abutting thereagainst if desired, is a second pair of insulating means 24 and 25, indicated in the drawings as structurally identical to the insulating means 22 and 23. The pair of insulating means or bands 24 and 25 may be of the same width as the heat barriers 22 and 23, although this is not at all times required, and additional pairs of insulating means may be positioned adjacent or abutting against the bands 24 and 25. The insulating means 24 and 25 are effective to reduce heat transfer from the shell interior through the shell walls to the sheet edge portions Wa and Wb which, as noted, may be of reduced thickness as compared with the remainder of the web W, or may in some other manner be inclined to dry more rapidly, if subjected to the same amount of heat.

An exemplary form of insulating means is shown in FIGURES 2 and 3, and may be seen to comprise a strip, sheet, layer or band or fibrous insulative material 26 lying in flush fitting contact with the shell inner periphery, a strip, sheet, band or layer of metal 27 to which the in-

sulative material 26 is secured, as by adhesive means 28, and clamping means or securing means generally indicated by the numeral 29. The insulative material 26 is preferably of woven fibrous structure having the necessary strength for the instant application and of sufficient porosity such that substantial volumes of condensate are not retained therein to markedly reduce the insulative characteristic of the heat barrier band 26. The insulative band or sheet may be provided by a number of materials, exemplified by woven fiber glass, woven polymeric fibers typified by nylon, Dacron and the like, asbestos tape or sheeting, and other natural and synthetic woven or knit materials having low rates of heat transfer. A commercially available material is asbestos tape No. 1096 offered for sale by Johns-Manville Corp.

In a typical application the insulative material 26 may have a thickness of $\frac{1}{16}$ inch and a width of six inches, and of course, the metal sheet 27 is desirably of the same width and may be of the same thickness. Stainless steel is a metallic material suitable for the metal band 27. Various adhesives or glues may be employed to secure the insulative band 26 to the metal sheet 27 and adhesive means is preferred as the mode of securement, although of course screws or other devices could be driven into the shell 11.

The insulative band 26 and metal band 27 are split transversely as indicated at 30, and opposite ends of the split metal band 27 may be forced apart to secure the insulative assemblies 22-25 to the drum inner periphery by the clamping means 29. The clamping 29 may take the form of bracket means 31 and 32 welded or otherwise secured to the metal band 27 outwardly of the split 30, and each bracket 31 and 32 may have an upstanding portion 31a or 32a apertured to receive bolt means 33 threadably engaged by two sets of cooperating nut means 34 and 35.

It may now be seen that by provision of the circumferential insulating bands 22-25 heat losses to the ambient atmosphere are reduced simply, readily and economically. The web edge portions Wa and Wb are now protected by an effective heat barrier which prevents substantial over-drying of the web edge portions, and as well, heat losses from the shell interior through the exposed drum end portions 11a and 11b are also markedly reduced. The asbestos or other insulative sheet material 26 of course absorbs the condensate outwardly of the drum central portion, and there is thus obtained the insulative value of the heat barrier material 26 coupled with the insulative effect of the water retained in the insulative material.

It is known that stainless steel is a relatively poor heat conductor, and it is accordingly possible that the sheet or band 27 could be employed by itself without the fibrous insulation sheet 26. However, experience has indicated that the stainless steel sheet by itself has a tendency to slip along the shell inner periphery, and that the metal band does not generally make the desired flush fitting contact with the inner periphery of the shell 11. When the asbestos or like sheet 26 is present, however, slippage is essentially entirely eliminated, a close fitting contact is provided and heat transfer reduced substantially over that which occurs when only a relatively wide metal band is employed.

It has been previously suggested that if the drum 10 is to be operated at speeds below which "rimming" of the condensate occurs in the central portion of the shell, paddles or baffles can be mounted in the drum central portion to induce rotation of the condensate therewithin. While this might also be desirable in the instant application, it is pertinent to note that since the insulative bands 26 are absorbent and thereby retain condensate, paddles or baffles would not be required to the same extent as in a drum structure wherein levels of condensate were the insulators provided.

The instant application drawings disclose a single split 30 in the fibrous and metal bands 26 and 27. To facilitate installation it may be desired to employ multi-part bands

26 and 27, as for example, three or four piece bands 26 and 27. As well, as was noted, the number of insulating means 22-25 may be less than or greater than that illustrated in FIGURE 1.

It will also be appreciated that the instant invention is of important application in the control of heat input to the web throughout an entire dryer section, which may include as many as fifty dryer drums. In such an arrangement, the insulative means within the dryer drums are positioned at different locations throughout the dryer section, so that the amount of heat input to the central portion of the web may be correlated with that input to the web edges *Wa* and *Wb*. Stated otherwise, the insulative means of the character indicated at 22-25 in FIGURE are positioned so as to produce a contoured curve of total heat input to the web. Illustratively, in a paper machine having a dryer section of fifty dryers, the insulative means can be successively moved toward the center of the machine in such a manner that the edges of the web would receive a heat input of 60% of the input at the center of the machine or dryer, and by properly arranging the insulative means, the total heat input at intermediate points would be precisely adjusted to the desired moisture profile, and/or to the particular characteristics of drying due to ventilation and other factors.

In such a paper machine dryer section, the circumferential insulative bands within the dryer drums are moved progressively inward toward the center of the drums in the direction of web travel, from the oncoming to the off-running side of the dryer section, and with such insulative bands mounted in the drums in this manner, a substantially uniform ratio between the heat input to the central portion of the web and that to the edges may be maintained throughout the length of the dryer section.

It will be understood that modifications and variations may be effected without departing from the spirit and scope of the novel concepts of the present invention.

I claim as my invention:

1. A dryer drum comprising a cylindrical shell, a head closing each end of the shell, a steam inlet line leading 40 into the shell through one of said heads, axially spaced and axially adjustable insulative means including a fibrous insulative band in flush fitting contact with the shell inner periphery and stationarily carried thereby, said insulative means being positioned on the shell inner periphery so that an inner face thereof will contact the steam brought into the shell by said steam inlet, a condensate drainage

line communicating with the inner surface of the shell only, and said insulative means being positioned between the condensate drainage line and the shell heads reducing heat transfer through the drum shell.

- 5 2. A dryer drum comprising a cylindrical shell having a smooth and uninterrupted inner periphery between opposite ends thereof, a head closing each end of the shell, a steam inlet line leading into the shell through one of said heads, a condensate drainage line leading from the 10 shell through one of said heads receiving steam and condensate from the shell, an axially spaced circumferential insulative means on the shell inner periphery near the shell ends and having an inner face that is in contact with steam brought into the inner shell by said steam inlet for 15 reducing heat transfer through said shell, each of said insulative means comprising a water absorptive woven fibrous strip stationarily carried by and in close fitting contact with the shell periphery and a metal backing band secured to said fibrous layer.
- 20 3. A dryer drum comprising a cylindrical shell having a smooth and uninterrupted inner periphery between opposite ends thereof, a head closing each end of the shell, a steam inlet line leading into the shell through one of said heads, a condensate drainage line leading from the 25 shell through one of said heads receiving steam and condensate from the shell, an axially spaced circumferential insulative means on the shell inner periphery near the shell ends having an inner face in contact relationship with steam that is brought into the shell by said steam inlet for reducing heat transfer through said shell, each of said means comprising a fibrous band in close fitting contact with the shell inner periphery and rigidly carried thereby, a transversely split metal backing adhesively secured to said fibrous band, and means clampingly engaging 30 35 the metal backing at opposite sides of the transverse split.
